PIERRE EMILE JÉRÔME MENGIN, OF MONTARGIS, FRANCE

DOUBLE-ACTING HYDRAULICALLY-CONTROLLED PUMP

Application filed April 5, 1927, Serial No. 181,213, and in France February 8, 1927.

My invention has for its object an improved double acting hydraulically controlled suction and pressure pump. I have already built pumps of this type wherein the pump 5 piston is disposed vertically and is borne by a rod the ends of which act as plunging pistons inside two receiving cylinders connected through suitable pipings with the two chambers of a double acting press, which gives 10 these plunging pistons and consequently the piston pump which is secured to them an alternating movement.

A form of execution of such a pump comprises two suction and two pressure pipes for 15 the liquid to be pumped, these pipes leading each to one of the chambers of the pump and disposed laterally with reference thereto, the corresponding valves being disposed respectively in a suction and a pressure valve box, 20 both boxes being disposed in the axis of the pump.

In the improved pump which is described hereinbelow the lateral suction and pressure tubes are disposed in alignment one with the 25 other.

This arrangement shows the following advantages: The flanges at the extremities of the pump body where these pipes end require only in this case one single channel which 30 allows the corresponding chamber of the pump to communicate with the suction and the pressure sides.

By reason of the reciprocating movement of the piston, the liquid columns in the pressure and suction tubes are submitted periodically to water hammer effects at each corresponding stoppage of the piston. Thanks to my improved arrangement allowing the two liquid columns to be in alignment the vis viva 40 of these water hammer effects is no longer lost; the moving pressure column instead of stopping will suck the suction column whereas the moving suction column instead of stopping will urge forward the pressure column. 45 The detrimental action of the water hammer

effects on the parts of the pump is thus minimized.

Lastly this arrangement of the suction and pressure tubes in alignment allows a general symmetrical disposition to be given to the 50 pump with reference to its axis so that the stresses transmitted to the pump device by the controlling press and by the pressure and suction tubes will remain constantly symmetrical. These stresses will therefore appear in 55 equilibrium whereby the pump when working will not be submitted to any motion or vibration. The mounting of these several parts may be executed in a very advantageous manner by using for the lateral suction and pressure tubes thin metal tubes either of steel 60 or of a more malleable metal such as brass, the said tubes being secured by chucking in the end flanges of the pump body and in the valve boxes. This manner of securing them 65 provides perfect watertightness and considerable resistance against the wrenching out of the tubes. The pump system obtained in this manner is absolutely rigid and of a very simple construction whereby the size of the cross 70 section of the system can be considerably reduced and the pump can be lowered into very narrow bored shafts. The reason is that by connecting as stated the pump body with the valve boxes by means of lateral pipes, all the 75 devices such as struts, stays and the like which were thought up till now necessary for connecting these parts are done away with. Besides the comparatively important flexibility of these lateral pipes makes the pump system 80 less liable to be broken.

The number of lateral suction and pressure pipes disposed symmetrically and in alignment one with reference to the other is chosen so as to give the total liquid section required 85 by the output of the pump; the rigidity of this arrangement increases with the number of pipes.

My invention provides also, in a pump of the aforesaid type, for the particular arrange- 90

ment of certain parts thereof as will be described hereinafter.

By way of example, I have described hereinbelow and shown on appended drawings a form of execution of a pump according to my 5 invention:

Fig. 1 is a front view partly sectional,

Fig. 2 shows in detail the piston of the pump,

Fig. 3 shows a modified form of the cylinder of the receiving press for pumps of large 10 diameter.

Figs. 4 and 5 are a partly sectional front 15 view and plan view of a valve.

The pump body is closed at its upper part 20 by a flange or cover 2 and at its lower part by a flange 3. It comprises a piston 4 mounted on a rod 5 the two ends 8 of which act as plunging pistons in two small cylinders 9 and 10; the upper cylinder 9 and the lower cylinder 10 communicate respectively through the tube-openings 11 and 12 and corresponding pipes not shown with the two chambers of a double acting hydraulic press not shown 25 which is disposed at the point wherefrom the pump is to be hydraulically actuated.

The double acting controlling press may be constituted for instance by two opposed bodies wherein two plunging pistons secured 30 one to the other are adapted to move. There is thus provided in the two cylinders 9 and 10 alternately a pressure and a suction of the liquid whereby the rod 5 and the piston 4 are given a reciprocating motion.

The top chamber 13 of the pump body 1 is 35 connected through the opening 14 provided in the flange or cover 2 with the suction pipe 15 and the pressure pipe 16. In a similar manner the lower chamber 17 of the pump body is connected with the suction pipe 18 and the 40 pressure pipe 19. The two suction pipes 15 and 18 lead to the suction box 20 wherein is disposed a valve such as 21 at the end of each pipe. This box 20 communicates through an 45 opening with a pipe plunging in the liquid to be pumped. In a similar manner the pressure pipes 16 and 19 are connected with a pressure valve box 22 containing for each pipe a valve such as 23 and the top of which is connected with the pressure pipe not shown.

As shown on the drawings, the tubes 15 and 16 are disposed on the cover 2 so as to be in alignment one with the other. Similarly the tubes 18 and 19 are disposed on the cover 3 55 so as to be in alignment one with the other.

The pipes 15 and 16 on one hand and 18 and 19 on the other are disposed on either side of the pump body and in the central plane thereof.

This aligned symmetrical arrangement of the lateral suction and pressure tubes provides the abovementioned advantages consisting in that the covers 2, 3 bears each only one canal such as 14, that the water-hammer 60 effects in 15—16 and 18—19 have only a very

slight action on the pump body itself, that the forces acting on the pump are constantly symmetrical and have a resultant equal to zero on the axis so that the pump body is not submitted to any vibration or movement, this pump body hanging generally on the pressure pipe ending at 22 and on the hydraulic transmission pipes ending at 11 and 12 without being secured otherwise in the shaft into which it has been lowered.

The suction or pressure pipe such as 16 is secured to the cover such as 2 and the valve box such as 22 in the following manner. The tube is in thin metal, for instance of steel or brass; the part which is to receive its end for instance the flange 2 shows a groove 24 wherein in the tube is driven by means of a chuck. This connecting arrangement ensures excellent watertightness and a great resistance against wrenching out. It obviates the need of any other connection between the pump body 1 and the suction and pressure valve-boxes 20 and 22. The pump arrangement is thus very compact and takes up laterally very little room. However the lateral pipes and their manner of being assembled gives the pump a certain elasticity which makes it less liable to be broken.

To provide a good watertightness for the piston 4, its packing comprises two leather cups 25, 26 (Fig. 2) held between two plates 27, 28 connected by bolts 29 and secured to the collar 30 of the piston rod 5 by means of a nut 31 passing round the rod and screwed into one of the plates, 28 for instance. In 95 order to prevent undesired movements of the leather cups 25, 26 principally during the pressure strokes, a thin disc 32 is inserted between the two cups.

In the apparatus shown on Fig. 1 the driving pistons 8 are plunging pistons formed by the rod 5 of the pump piston 4. This rod is full or hollow, in which latter case it is closed by a threaded plug. The end of the piston may be hollowed out at 34, the hollowed out portion being provided at its basis with a series of peripheral apertures 35. The watertightness of the plunging piston is ensured by the leather cup 36. When the said piston arrives at the end of its driving stroke the holes 35 pass beyond the leather cup 36 so that the play existing at 37 in the guiding passage of the plunging piston allows these apertures to make the chamber under pressure 38 communicate with the top chamber 13 of the pump body. The result is that if the impulse given by the liquid under pressure at 38 is not ended when the piston 4 arrives at the end of its stroke, the liquid under pressure in the chamber 38 is allowed to pass into the chamber 13. The damages which might be made in the transmission pipes by an excess pressure are thus avoided.

In the case of large diameter pumps, the plunging pistons such as 8 would show draw- 130

backs chiefly on account of their weight and of their cost or replacement. Another form of execution of these pistons shown on Fig. 3 comprises a piston 40 of the ordinary type provided with a packing cup 41 of leather or other material and borne by the rod 39 of the piston 4 which has a comparatively small diameter. The driving cylinder 42 is provided with an inner easily replaceable sleeve 43 of suitable metal. This sleeve is provided at its top end with a series of small peripheral apertures 44 which allow when the cup 41 has passed beyond them the chamber 45 of this driving cylinder to communicate with the chamber 17 of the pump body 1 through a chamber 46 the diameter of which is slightly superior to that of the chamber 45, the top of the sleeve 43 with its apertures 44 being disposed inside the said chamber 46.

The ends of the driving pistons such as 8 (Fig. 1) are preferably provided with a tapped hole 47. When the pump is taken to pieces, a rod showing a terminal thread may be engaged into this hole after passing through the corresponding cylinder 9; the piston 4 and the rod 5 may thus be lifted whereby the lower part of the apparatus (lower driving cylinder 10 and casing 1) can be more easily removed.

Each valve comprises (Figs. 4 and 5) a seat 48 secured between two joined parts of the valve box. This seat shows a circular opening 49. In this opening are left arms 50, 51, 52, 53 the centre of which supports an upwardly directed stem 54. This stem serves to guide the valve proper constituted by a disc 55 of slightly yielding material such as hard rubber, leather, fibre disposed round the stem 54 and held in position by the sliding washer 56 pressed down by the spiral spring 57, this spring being held in its turn by a cup 58 secured by a pin 59 passing through the guiding stem 54 and disposed in a recess of the outer surface of the cap 58.

The radial arms 50, 51, 52, 53 are not flush with the top surface of the seat 48 of the valve 55.

This arrangement provides a very large passage 49 for the liquid and the valve 55 bears on a regular circular seat of large surface so that it can rotate round the stem 54 without its wear or deformation being ever detrimental to its watertightness.

The suction and pressure valve boxes 20 and 22 are not symmetrical; the lower part of each of them is less high than the valve guiding stem which is to be disposed in the top part. Thereby no faulty inverted mounting of the valves in their boxes need to be feared.

What I claim is:

1. In a double acting hydraulically controlled pumping apparatus comprising a pump body, a reciprocating piston adapted to move therein and hydraulic means acting

on the ends of the piston rod and adapted to give latter a reciprocating movement, the combination of two couples of two aligned straight pipes having a uniform section throughout their length and opening without restriction one into the other, a lateral opening being provided between the adjacent ends of the pipes of each couple of pipes, means whereby each end of the pump body is in direct and permanent communication with the opening in one of the couples of pipes and a suction valve box and a pressure valve box respectively in connection with one pipe of each couple of pipes.

2. In a double acting hydraulically controlled pumping apparatus comprising a pump body, a reciprocating piston adapted to move therein and hydraulic means acting on the ends of the piston rod and adapted to give latter a reciprocating movement, the combination of two couples of two aligned straight pipes independent of the pump body, disposed symmetrically one with reference to the other, having a uniform section throughout their length and opening without restriction one into the other, a lateral opening being provided between adjacent ends of the pipes of each couple of pipes, a substantially T-shaped duct secured to each end of the pump body and to each pipe of one of the couples of pipe for ensuring unrestricted communication between the pipes of this couple together with direct and permanent connection with the corresponding end of the pump body and a suction valve box and a pressure valve box both independent of the pump body respectively in connection with one pipe of each couple of pipes.

3. In a double acting hydraulically controlled pumping apparatus comprising a pump body, a reciprocating piston adapted to move therein and hydraulic means acting on the ends of the piston rod and adapted to give latter a reciprocating movement, the combination of two couples of two straight pipes of thin metal independent of the pump body, disposed symmetrically one with reference to the other, having a uniform section throughout their length and opening without restriction one into the other, a lateral opening being provided between adjacent ends of the pipes of each couple of pipes, a substantially T-shaped duct secured to each end of the pump body and punched over the end of each pipe of one of the couples of pipe for ensuring unrestricted communication between the pipes of this couple together with direct and permanent connection with the corresponding end of the pump body, a suction valve box and a pressure valve box both independent of the pump body and covers secured over each valve seat of each box and punched over the end of the corresponding pipe.

4. In a double acting pumping apparatus

as claimed in claim 1, an auxiliary piston
borne by each extremity of the piston rod
and on which the hydraulic means are
adapted to act, a cylinder for each auxiliary
5 piston, a sleeve for said cylinder wherein the
auxiliary piston is adapted to slide and pro-
vided with apertures providing a communica-
tion with the pump body, said apertures
being uncovered by the auxiliary pistons at
10 the end of their driving stroke.

In testimony whereof I affix my signature.
